Primary Examiner — Katie Jane Stofko(57) **CLAIM**

The ornamental design for a game board, as shown and described.

DESCRIPTION

FIG. 1 is a front and top perspective view of a game board, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front and top perspective view thereof, shown in an alternate position;

FIG. 10 is another front and top perspective view thereof, shown in an alternate position; and,

FIG. 11 is an enlarged perspective view of detail “11” identified in FIG. 10.

The dashed lines in the figures illustrate portions of the game board that form no part of the claimed design. The dash dot dash lines in FIGS. 10 and 11 are for the purpose of illustrating the enlarged view indicators and form no part of the claimed design.
